ATTORNEY.

UNITED STATES PATENT OFFICE.

CHARLES C. STEWART, OF STODDARD, ARIZONA.

WRENCH.

1,392,238.

Specification of Letters Patent. Patented Sept. 27, 1921.

Application filed May 5, 1920. Serial No. 379,115.

To all whom it may concern:

Be it known that I, CHARLES C. STEWART, a citizen of the United States, residing at Stoddard, in the county of Yavapai and 5 State of Arizona, have invented certain new and useful Improvements in Wrenches; and I do hereby declare the following to be a full, clear, and exact description of the invention, such as will enable others skilled 10 in the art to which it appertains to make and use the same.

This invention relates to a wrench, and more particularly to an implement of the type indicated designed for use either as a 15 pipe wrench or a monkey wrench.

One object of the invention is to provide in connection with a stationary jaw and a relatively movable jaw, a block, slideable with reference to one of said jaws, and movable 20 toward the other jaw when pressure is applied to the handle, the block being retained in a stationary position and with its working face substantially parallel with the face of the other jaw, when the tool is 25 used as a monkey wrench.

A further object is to provide in connection with a stationary jaw and a relatively movable jaw, a block having a beveled surface coöperating with an inclined surface 30 formed on one of the jaws, and to provide in connection with such structure suitable guiding and retaining elements.

A still further object is to provide in connection with a stationary jaw and a relatively movable jaw, a block one surface of which is substantially parallel with the opposing surface or working face of the movable jaw, the block, converging slightly with reference to the opposing face of the other 40 jaw, and means for guiding the block and permitting it to move longitudinally and toward and away from the movable jaw.

A still further object is to provide, in a device of the class indicated, particular 45 means for retaining the movable block, and permitting the limited movement thereof, and resilient means mounted in a particular manner for restoring the block to its outer or normal position when the handle 50 is relieved of the pressure applied during the operative movement of the device used as a pipe wrench.

With the foregoing and other objects in view, the invention consists in the novel 55 construction, combination, and arrange-

ment of elements hereinafter described and claimed.

In the accompanying drawings—

Figure 1 is a plan view of the wrench, with elements in dotted lines. 60

Fig. 2 is a transverse section through the movable block and portion of the stationary jaw on which it is mounted.

Fig. 3 is a bottom plan view of the movable block. 65

Figs. 4 and 5 are details of construction described below.

In carrying out my invention I employ a stationary jaw 10 and a relatively movable jaw 12, the shank portion 13 of the latter 70 being threaded in the usual manner, as shown at 14, and being engaged by threading sleeve 15.

The stationary jaw 10 is inclined in the direction shown and is provided with a 75 dovetailed groove 17 with which the tongue 18 of the movable block 20, coöperates.

The surface 21 of the block 20 is substantially parallel with the surface 22 of the movable jaw. The toothed portions 22' 80 and 21' tend to converge slightly, so that a pipe or rod engaged by the jaws will be clamped thereby.

The block 20 is provided with an aperture 25 in the lower side thereof, the aperture 85 communicating with the slot 26 and a stop pin 27 passes through a bore 28 in the stationary jaw, and the end of the pin or stop enters the aperture 25, for retaining the jaw in proper position, and preventing the outward movement thereof. The head 29 of the stop pin is provided with notches 30 and 31 on opposite sides thereof, and either of the notches may be engaged by a key 32, normally forced outwardly by a spring 33. 90

This key is cut away at its outer end, and the projecting portion 34 extends slightly over from the outer surface when the elements are in operative position. The upper end, or inner end, of the pin 27 is cut away 100 as shown, to form a projecting element 36, and when the pin is turned in a given position this projecting element will engage the walls of the aperture 25 positively and prevent the outward movement of the slideable block. One of the notches in the head of the stop pin 27 is then engaged by the key 32. This key is released and the pin rotated through a half revolution, the other of said notches in the head being engaged 105 110

by the key, and the element or bit 36 on other end is then positioned to coöperate with the slot 26, these elements being of the proportion shown. The block is then released and moves inwardly when pressure is applied to the handle in the use of the device as a pipe wrench.

The bore or well 38 in the movable jaw receives a flat spring 39 having an element 10 40 for one end thereof, the latter being approximately of the same cross section as the cross section of the bore. The free end of the spring coöperates with the notch 42 in the block, for the purpose of restoring 15 the latter to normal position. The movement of the block is limited to the extent determined by the space between the inner end of the block and the shank portion of the jaw 12, and the pipe is not damaged by 20 undue movement of the block and unnecessary gripping action resulting therefrom.

In the use of the device it is not necessary at all times to set the block 20 rigidly with reference to the stationary jaw when turning up for using the device on pipes or as 25 a monkey wrench, since the block will remain sufficiently stationary for the purpose indicated, but the stop pin 27 is desirable when making use of the tool as a monkey 30 wrench. The faces 21 and 22 of the jaws being substantially parallel, the corners of a nut are not cut nor damaged and the same remark holds true though the toothed portions of the jaws also engage the nut to a 35 slight extent, since the toothed portions converge gradually.

It will be observed that no screws or rivets are required in assembling the elements, and in removing the slideable block, it is only 40 necessary to depress the spring key 32 and then withdraw the stop pin 27. While I have shown the improvements as applied to a well known type of wrench, it is obvious that the particular arrangement of the main 45 jaws, such as 10 and 12, is immaterial, and it is further clear that details of construction may be varied within the scope of the appended claims.

What is claimed is:—

50 1. In a device of the class described, a stationary jaw, a movable jaw, a working block slideable along the face of the stationary jaw, and having tongue and groove connection therewith, said block having an opening 55 therein and a slot communicating with the opening, a stop pin passing through the sta-

tionary jaw and entering said opening, said pin having a reduced end portion, the reduced portion coöoperating with the opening and slot and being adapted to retain the block against slideable movement and at times to permit of limited slideable movement, and a key for retaining said pin in position to perform either of said functions.

2. In a device of the class described, a stationary jaw, a movable jaw, the stationary jaw having an inclined face, a block wedge shaped in cross section, having tongue and groove connection with the jaw first named and slideable with reference thereto, the working face of the block and the working face of the movable jaw converging at their inner portions, resilient means for normally forcing the block outwardly to inoperative position, the block having an opening therein and a slot communicating with the opening, a stop pin having a reduced end portion cooperating with said opening and the slot and adapted to retain the block in a given position and to retain it at times in a position permitting limited slideable movement, said pin including a head having notches in opposite sides thereof, and a spring held locking key adapted to engage either of said notches.

3. In a device of the class described, a stationary jaw, a movable jaw, a working block slideable along the face of the stationary jaw and having a tongue and groove connection therewith, said block having a slot extended therein from one edge and terminating in an enlarged opening or head at its inner end, a stop pin passing through the stationary jaw and entering said slot, said pin being formed so as to be turned to serve as a guide for the working block and permit movement thereof on the stationary jaw, said pin being also adapted to be turned in the head of the slot to lock the working block against slideable movement on said stationary jaw, means to retain said stop pin in adjusted position and prevent displacement or loss of said stop pin, and means carried by said stationary jaw to resiliently retain said working block in one position on said stationary jaw.

In testimony whereof I affix my signature in presence of two witnesses.

CHARLES C. STEWART.
